UNITED STATES PATENT OFFICE

ANDREW McANDREW, OF NORTH LITTLE ROCK, ARKANSAS, ASSIGNOR OF ONE-HALF
TO WILLIAM J. HYNES, OF NORTH LITTLE ROCK, ARKANSAS

GRINDING FIXTURE

Application filed March 22, 1927. Serial No. 177,354.

This invention relates to grinders and more particularly to a device for grinding milling and other cutters.

Cutting tools such as "face mills" for milling machines are commonly provided with a series of cutters or teeth, each of which is formed with a peripheral surface and a side surface, each terminating in a cutting edge, and a corner or intermediate cutting portion connecting the side and peripheral edges. This corner portion is, on large mills, usually formed of a plurality of connected, yet distinct, cutting edges which together approximate a curve and which I have in this case defined as the radius of the teeth.

A primary object of the invention is to provide a device capable of grinding the face, radius and sides of both large and small milling cutters and backing off to proper clearance in one operation.

Another object is to so construct such a grinder that it will accurately grind a perfect radius or arc of any size.

Another object is to provide a grinding unit of this character which is very compact and can be made of different sizes and used on any standard full universal or plain grinding machine.

In carrying out these objects the invention is susceptible of a wide range of modifications without departing from the spirit or sacrificing any of the advantages of the claimed invention; there being shown in the drawings for illustrative purposes certain preferred and practical forms, in which:-

Figure 1 represents a side elevation of a grinding fixture constructed in accordance with this invention, shown in use,

Fig. 2 is a similar view with the fixture in a position at right angles to that shown in Fig. 1,

Fig. 3 is a horizontal section with parts broken out and in section,

Fig. 4 is a detail transverse section of the base member,

Fig. 5 is a detail showing the path of the grinding wheel, and

Fig. 6 is a vertical section of the knee with parts of its support broken away.

In the embodiment illustrated a base plate 1 is shown adapted to be fastened to the machine plate, not shown, which carries the original cross and longitudinal feeds of the machine. This base plate 1 is shown circular in form with laterally extending attaching lugs or ears 2 arranged at diametrically opposite points and having open slots 3 therein to receive the fastening elements 4. This base member 1 has an annular groove 5 extending around its upper face near its periphery and which is inverted T-shaped in cross section and designed to receive adjustable stops in the form of bolts 6. These stops 6 are insertable through an opening 7.

A rotary motion member 10 is mounted on the base 1 and is used for the grinding of the radius or arc of the cutter teeth, said arc being located between the radial or peripheral members or legs of said teeth. This member 10 has on its upper face a transversely extending undercut cleat 10^a adapted to slide in a correspondingly shaped seat 11^b formed transversely in the lower face of a superposed plate 11. This plate 11, is adjusted by screw 12 to locate the cutter on either the right or left of the center as may be desired, a handle for operating screw 12 being shown at 12^a in Figs. 2 and 3.

A plate 13 is mounted on top of plate 11 and arranged at 90° from the cleat or gib 10^a on the rotary member 10 and is adapted to slide on plate 11 on a transverse undercut cleat 11^a fitting in a corresponding seat 13^a of plate 13.

An angle bracket or knee 15 is adjustably mounted on plate 13 to adapt it to the work to be performed on the machine to which the device is applied. The upright member 15^a of this knee 15 is bored above its center at an angle of 30° to a perfect ball socket 16

designed to receive a ball 18 carried by an arbor 17 and which provides clearance for the arbor. This ball 18 is nicely ground and fitted in socket 16 and is retained in place by 5 a locking plate or collar 20, held by four cap screws 20^a. This lock plate is fitted to the rear face of the knee 15 and is bored on an angle, as shown at 21, to provide ample scope for the arbor 17 when assembled. When the 10 degree required for angles of various cutters is determined, the arbor 17 can be locked to the knee 15 by plate 20 and the cutter 25 is ready for grinding since it rotates freely on the arbor 17, a collar 19 on said arbor forming 15 an abutment for the cutter.

Means for arresting the motion of the cutter while grinding, is shown in the form of a finger 22, which is placed under the blade of the cutter being ground, to hold it in position 20 while grinding. This finger 22 may be placed either on the fixture or on the head of the grinding machine. When the ball 18 is set to the degree required to properly position the cutter to be carried thereby, it is firmly locked and the cutter is adjusted to the finger by turning on the arbor 17 since the cutter is not driven on but held by a well seated bushing placed on the arbor. The path 25 of the grinding wheel 30 relative to a cutter tooth or blade 26, is shown in Fig. 5 and the grinding of the cutter is begun on the side of the point where the radius or arc begins which is determined by the stop 24 on the longitudinal movement of the grinding machine table 30. When this stop is reached the rotary member 10 comes into play and is moved to cause the blade to engage the grinding wheel 30 until it reaches the end of its radius or arc, which is governed by the stop 6 on base 1 after 35 which the face of the cutter is ground by the longitudinal movement of the machine table. This operation completes the grinding of one blade 26 of the cutter 25. The cutter is then swung on the arbor 17 to bring the next blade 40 in position, the face or leg 26^a of the cutter being first ground, then the radius or arc 26^b and last the side or leg 26^c, and so on until all of the teeth or blades of the cutter are finished. With the cutter 25 shown, when 45 the blades on one half are ground the cutter is removed from the arbor and turned around and the operation above described is repeated. The above description applies to staggered helical cutters which continue 50 across the face and can be ground in one continuous operation,—this, of course, applies to 55 one blade at a time.

I claim:—

1. A grinding machine including an upper 60 slide, a knee adjustably mounted on said slide and having an upstanding member provided with a ball socket located above its center, an arbor having an integral ball formed intermediate its ends and fitting said socket, and 65 means for locking said ball within said socket

and thereby holding the arbor in adjusted position.

2. A grinding machine including an upper slide, a knee adjustably mounted on said slide and having an upstanding member provided with a ball socket, an arbor having a ball formed intermediate its ends and fitting said socket, a collar for locking said ball within said socket and thereby holding the arbor in adjusted position, said collar having the opening 70 therein formed at an angle to provide ample scope for the arbor. 75
